CLAIM

The ornamental design for a bleacher cover, as shown and described.

DESCRIPTION

FIG. 1 is a perspective view of a first embodiment of a bench cushion mounted to a bench with both opposed sides of the bench being covered;

FIG. 2 is a front view of the bench cushion shown in FIG. 1 when laid flat;

FIG. 3 is a rear view of the bench cushion shown in FIG. 1 when laid flat;

FIG. 4 is a left side view of the bench cushion shown in FIG. 1 when laid flat;

FIG. 5 is a right side view of the bench cushion shown in FIG. 1 when laid flat;

FIG. 6 is a top view of the bench cushion shown in FIG. 1 when laid flat;

FIG. 7 is a bottom view of the bench cushion shown in FIG. 1 when laid flat;

FIG. 8 is a perspective view of a second embodiment of the bench cushion shown in FIG. 1 mounted to the bench with one side of the bench being covered;

FIG. 9 is a front view of the bench cushion shown in FIG. 8 when laid flat;

FIG. 10 is a rear view of the bench cushion shown in FIG. 8 when laid flat;

FIG. 11 is a left side view of the bench cushion shown in FIG. 8 when laid flat;

FIG. 12 is a right side view of the bench cushion shown in FIG. 8 when laid flat;

FIG. 13 is a top view of the bench cushion shown in FIG. 8 when laid flat;

FIG. 14 is a bottom view of the bench cushion shown in FIG. 8 when laid flat;

FIG. 15 is a perspective view of a third embodiment of the bench cushion mounted to the bench with no covering on the opposed sides;

FIG. 16 is a front view of the bench cushion shown in FIG. 15 when laid flat;

FIG. 17 is a rear view of the bench cushion shown in FIG. 15 when laid flat;

FIG. 18 is a left side view of the bench cushion shown in FIG. 15 when laid flat;

FIG. 19 is a right side view of the bench cushion shown in FIG. 15 when laid flat;

(Continued)

FIG. 20 is a top view of the bench cushion shown in FIG. 15 when laid flat; and,
 FIG. 21 is a bottom view of the bench cushion shown in FIG. 15 when laid flat.

The broken line showing a bench is for the purpose of illustrating the environmental structure and forms no part of the claimed design.
